UNITED STATES PATENT OFFICE.

HANS LUTZ, OF ELMIRA, NEW YORK, ASSIGNOR TO THE WILLYS-MORROW COMPANY, OF ELMIRA, NEW YORK, A CORPORATION OF OHIO.

GRINDING MACHINE.

Application filed October 6, 1920. Serial No. 415,127.

To all whom it may concern:

Be it known that I, HANS LUTZ, residing at Elmira, county of Chemung, State of New York, have invented certain new and 5 useful Improvements in Grinding Machines, of which I declare the following to be a full, clear, and exact description.

My invention relates to grinding machines and has for its object to provide a machine 10 of improved construction for grinding the discs or rings or other grinding parts used in the grinding of balls such as are employed in ball bearings.

Another object of the invention is to provide an improved grinding machine adapted 15 to simultaneously grind a plurality of rings or discs on which the grinding surfaces disposed at different angles to the axes of the rings.

Another object of the invention is to provide, in a grinding machine, a rotating 20 grinding wheel with improved means for holding and reciprocating the work upon the grinding surface of the wheel.

A further object of the invention is to provide improved means for supporting and rotating the work in contact with the grinding 25 element.

With these and other objects in view the 30 invention comprises certain novel features of construction and arrangement of parts as will be hereinafter more fully pointed out and claimed, it being apparent to those skilled in the art that the invention shown and described therein is susceptible to various modifications and arrangements to suit special or varying conditions, and I wish it to be understood that the terms which I have used are merely descriptive and not 35 limiting and that it is my intention to include any and all modifications which come within the scope of the invention as defined in the appended claims.

A construction constituting one embodiment 40 of the invention is illustrated in the accompanying drawings, in which:—

Figure I is a side elevation of a machine embodying the invention.

Figure II is an end elevation of the same, 45 with a portion of the base omitted.

Figure III is a top plan view of the portion of the machine shown in Figure IV with the grinding disc omitted.

Figure IV is a sectional elevation taken on line IV—IV of Figure II. 55

Figure V is a sectional elevation taken on lines V—V of Figures III and IV.

Figure VI is a detailed sectional view taken on line VI—VI of Figure V, and

Figure VII is a plan view of the frame 60 for supporting the slide shown in Figure III.

Like reference numerals refer to similar parts throughout the several views of the drawings.

Referring to the drawings, 10 represents 65 a base upon which is mounted a standard 11 having upstanding arms 12 provided with bearings 13 adapted to receive a shaft 14 upon the extremities of which are mounted the grinding wheels 15, said shaft being 70 provided between the arms 12 with pulleys 16 and 17 of different sizes to permit the shaft to be driven at different rates of speed by means of a belt 18. Cylindrical members 19 are mounted upon the base 10 at opposite 75 sides of the standard 11, and secured by means of bolts 20, the connection preferably permitting adjustment of the cylindrical members on the base. The mechanisms superimposed upon said cylindrical members 80

are similar in construction and a description of one will therefore suffice for both. Projecting within said cylindrical member 19 is a plunger 22 adapted to support a frame 23, upon which is superimposed the mechanism 85 for supporting and rotating the member to be ground in engagement with the grinding wheel 15. The plunger 22 is adjustable up and down within the cylinder 19 by means of a feed screw 24 rotatable in a head 25 on the upper end of the plunger which is actuated by means of a pinion 26

adapted to be rotated by a worm 27 on a shaft 28 journaled in bearing 29 and 30 on the frame 23, said shaft being actuated by means of a hand wheel 31 rotated by the handle 32 as shown in Figure VII. The screw 24 is threaded through a block 33 supported by an upright tubular member 34

100 into which the screw projects, said tubular member being carried by the bottom 35 of the cylinder 19 and secured thereon by means of the screws 36 as shown in Figure IV, it being understood that upon rotation 105 of the shaft 28 by means of the hand wheel 31 that the plunger 22 will be raised and

lowered within the cylinder 19 to move the work into and out of engagement with the grinding wheel 15. The frame 23 is rigidly held upon the plunger 22 by means of the 5 screws 37 which projects down through the central portion of the frame into the plunger. The cylinder 19 adjacent the top thereof is provided with horizontal and vertical slots 38 and 39 separating the upper portion of 10 the cylinder into two parts, each of which is provided with a lug 40 through which extends a bolt 41, which when sufficiently tightened serves to clamp the upper portion of the cylinder upon the plunger 22 to relieve the strain on the feed screw 24. Beneath the slot 39 the cylinder 19 is provided with a longitudinal slot 42 through which projects outwardly a stub shaft 43 rotatably mounted upon the plunger 22 in any suitable 15 manner, said shaft being adapted to move up and down in the slot 42 when the plunger is raised and lowered by means of the feed screw 24. Secured upon the shafts 43 are the pulleys 44 and extending from each of said pulleys inwardly are the belts 45 and 46, the former engaging a pulley 47 driven by a belt 48 and the latter engaging the pulley 49 driven by a belt 50, the pulleys 47 and 49 being rotatably mounted upon the 20 opposite sides of the standard 11. The frame 23 is provided with oppositely extending arms 51 having half round bearing portions 52 adapted to receive the opposite ends of a pair of rods 53 which are clamped 25 upon said bearing portions by means of the caps 54 secured by the bolts 55 as indicated in Figure III.

Reciprocally mounted upon the rods 53 is a slide having transverse portions 56 and 57 supported respectively by the bearing portions 58 and 59 of the slide through which the rods or guides 53 extend. The bearing portions 58 and 59 are split as indicated at 60 and adjacent said split portions are the downwardly extending lugs 61 through which extends bolts 62 as shown in Figures I and V. The bolts 62 are provided for the purpose of reducing the size of the bearings as the parts become worn. 40 The transverse portions 56 and 57 of the slide and the bearings 58 and 59 are connected by longitudinally extending side portions 63 as shown in Figures III and V. The side portions 63 are bored out to receive the reduced ends 64 of the bearing members 65 in which are positioned the bushings 66 to receive the opposite ends of the drive shaft 67, one end of which is provided with a sprocket 68 over which extends the upper 45 end of a sprocket chain 69, the lower end of which extends over a sprocket 70 on the shaft 43 journaled in the lower end of the plunger 22 and carrying the pulley 44 which is driven by the belt 45 as previously described. Secured upon the shaft 67 is a

worm 71 meshing with the worm gear 72 having a hub-like portion 73 rotatably mounted in the bearing 74 formed centrally upon the transverse portion 57 of the slide as shown in Figures III and IV. The worm gear 72 is held in position upon the bearing 74 by means of the screw bolts 75 extending downwardly through the cover plate 76 and into the hub-like portion 73 of the gear, said cover plate being rotatable upon a wearing plate 77 on the top of the bearing 74.

A cam 78 is positioned beneath the worm gear 72 and provided with an upstanding portion 79 extending through the center of the hub 73 of the gear and connected with said cover plate 76 by means of a screw bolt 80, which serves to clamp the cam upon the gear and to cause it to rotate therewith. The cam is adapted to rotate between two rollers 81 and 82 mounted on the upper ends of the bolts 83 and 84 respectively, the latter being adjustable in a slot 85 in the frame member 23 and the former screwed into the frame member as shown in Figure IV. The rollers are held upon the enlarged ends of the bolts by means of set screws 86 projecting into grooves 87 cut in the heads of the bolts. A bar 88 is clamped upon the frame 23 by means of the bolts 83 and 84 and superimposed upon the bar are the washers 89 upon which the rollers 81 and 83 are mounted to rotate. The washers may be of any desired thickness to vary the height of the rollers. The bar 88 is provided at its outer end with a slot 90 registering with the slot 85 in the frame member 23 to permit the bolt 84 and roller 82 to be adjusted inwardly or outwardly to accommodate cams of different sizes, when it is desired to vary the length of stroke of the reciprocally mounted slide upon the rods 53. Mounted to rotate or swing upon the bearings 65 for supporting the shaft 67 is a work supporting yoke or member 91, the extremities 92 of which encircle the bearings, the latter being clamped upon said extremities by means of the bolts 93 which serve to cause the annular flange therein to grip said extremities for the purpose of holding the yoke in any desired position of adjustment suitable to bring the work in engagement with the grinding wheel. The central portion of the yoke is provided with a bearing portion 94 in which is mounted a bushing 95 for receiving the shaft 96, the lower end of which is reduced to receive a pinion 97 adapted to mesh with the worm 71 on the shaft 67 as shown in Figure IV. The upper end of the shaft 96 is also reduced as indicated at 97 to receive the hub-like portion 98 of the grinding disc 99, the grinding surface 100 of which is brought into contact with the grinding wheel 15 as indicated in Figure I, said surface being ground to any desired angle with respect to the axis of the disc. A

washer 101 is disposed between the bearing portion 94 of the yoke and the hub-like portion 98 of the grinding disc, the latter being clamped and firmly held into position by the 5 nut 102 on the outer end of the reduced portion 103 of the shaft 96, which is driven by the shaft 67 through the worm 71 and worm gear 97. The grinding surface 104 of the grinding disc 105 is ground in a similar 10 manner to the disc 99, the disc 105 being provided with a hub-like portion 106 carried by the reduced portion 97 of shaft 96 and held thereon by the clamping nut 102 as shown in Figure I. The construction of 15 these parts is the same as the corresponding parts shown in Figure IV, with the exception of slight differences in proportion. As previously stated, the swinging or pivoted yoke 91 for supporting the grinding disc 20 or work piece in engagement with the grinding wheel is adjustable in a vertical plane, the extent of the adjustment being indicated by dotted lines in Figure VI.

During the operation of the machine the 25 grinding discs 99 also 105 are reciprocated back and forth upon the grinding wheels 15, which provides for even wear of the wheels, whereby the wearing of grooves or depressions therein is prevented, it being understood that the reciprocation of the slide, upon which the grinding discs are mounted is effected by means of the rotation of the cam 78 by means of the gear 72 and worm 71 on the shaft 67 driven by the sprocket 30 chain 69 which moves with the slide as the latter is reciprocated.

While I have illustrated and described one embodiment of my invention, it will be obvious to those skilled in the art that modifications thereof may be constructed without departing from the spirit of the invention and I wish therefore not to be restricted or limited to the precise embodiment shown except in so far as the same is limited by the 45 appended claims.

What I claim as new and desire to secure by Letters Patent is:

1. In a grinding machine, a base, a grinding wheel rotatably mounted upon the base, 50 a slide reciprocally mounted upon said base, a shaft rotatably mounted upon the slide, a gear driven by said shaft, a cam driven from said gear and adapted to reciprocate the slide upon the base and a work holder carried by the slide and driven from said gear to rotate the work in contact with said grinding wheel.

2. In a grinding machine, a base, a grinding wheel rotatably mounted upon the base, 55 a slide reciprocally mounted upon the base, a shaft rotatably mounted upon the slide, a worm upon said shaft, a gear connected with said worm, a cam driven by said gear and adapted to reciprocate the slide upon the base, and a work supporting shaft rotatably

mounted upon the slide to be driven by said worm whereby the work is rotated in contact with said grinding wheel.

3. In a grinding machine, a base, a grinding wheel rotatably mounted upon the base, 70 a slide reciprocally mounted upon the base, a shaft rotatably mounted upon the slide, a worm carried by said shaft, a gear driven by said worm, a cam operated by said gear to reciprocate the slide upon the base and 75 a rotatable work supporting member connected to be driven by said worm to rotate the work in contact with said grinding wheel.

4. In a grinding machine, a base, a grinding wheel rotatably mounted upon the base, 80 a slide reciprocally mounted upon the base, a shaft rotatably mounted upon the slide, a worm carried by said shaft, a gear connected with said worm, a cam actuated by said gear 85 to reciprocate the slide upon the base, a rotatable shaft mounted upon the slide and adapted to support the work in contact with said grinding wheel and a gear connected with said second shaft and meshing with 90 said worm to effect rotation of the work.

5. In a grinding machine, a base, a grinding wheel rotatably mounted upon the base, 95 a slide reciprocally mounted upon the base, a shaft rotatably mounted upon the slide, a gear adapted to be driven by said shaft, a cam rotated by said gear, a pair of rollers mounted upon the base between which the cam is adapted to rotate to reciprocate said slide, and a rotatable work holder actuated 100 by said shaft for effecting rotation of the work in contact with said grinding wheel.

6. In a grinding machine, a base, a grinding wheel rotatably mounted upon the base, 105 a slide reciprocally mounted upon the base, a bearing carried by said slide, a shaft rotatably mounted upon said bearing, a work holder mounted to swing upon said bearing and adapted to support the work in engagement with said grinding wheel, a gear 110 adapted to be driven by said shaft and a cam actuated by said gear and adapted to reciprocate the slide upon the base.

7. In a grinding machine, a base, a grinding wheel rotatably mounted upon the base, 115 a slide reciprocally mounted upon the base, a bearing member carried by the slide, a shaft rotatably mounted upon said bearing member, an arm pivotally mounted upon the bearing member, a work holding shaft rotatably mounted upon the arm and adapted to be driven by the first mentioned shaft to rotate the work in engagement with the said grinding wheel and means actuated by the first mentioned shaft for reciprocating 120 the slide.

8. In a grinding machine, a base, a grinding wheel rotatably mounted upon the base, 125 a slide reciprocally mounted upon the base, a bearing member mounted upon the slide, a 130

- shaft journaled upon said bearing member, an arm pivotally mounted upon said bearing member, a work holding member rotatably mounted upon said arm and adapted to rotate the work in engagement with the said grinding wheel, means driven by said shaft to effect rotation of said work holding member and means actuated by said shaft for reciprocating the slide on the base.
10. 9. In a grinding machine, a base, a grinding wheel rotatably mounted upon the base, a slide reciprocally mounted upon the base, a bearing member upon the slide, a shaft rotatably mounted upon the bearing member a holder pivotally mounted upon said bearing member, a shaft rotatably mounted upon the holder and co-operating therewith to support the work in engagement with said grinding wheel, means causing the second mentioned shaft to be driven by the first mentioned shaft and means actuated by the first mentioned shaft adapted to reciprocate the slide upon the base.
15. 10. In a grinding machine, a base, a grinding wheel rotatably mounted upon the base, a slide reciprocally mounted upon the base, a bearing member carried by the slide, a shaft rotatably mounted upon said bearing member, a member pivotally mounted upon said bearing member, a work holding shaft rotatably mounted upon said pivoted member and driven by the first mentioned shaft to rotate the work in engagement with the grinding wheel, and means actuated by the first mentioned shaft adapted to reciprocate the slide upon the base.
20. 11. In a grinding machine, a base, a grinding wheel rotatably mounted upon the base, a slide reciprocally mounted upon the base, a bearing member carried by the slide, a shaft rotatably mounted upon said bearing member, a member pivotally mounted upon said bearing member and adapted to rotate the work in engagement with said grinding wheel, a gear driven by the first mentioned shaft adapted to drive the second mentioned shaft and a cam actuated by the said gear and adapted to reciprocate the slide upon the base.
25. 12. In a grinding machine, a base, a grinding wheel rotatably mounted upon the base, a plunger adjustable vertically upon the base, a frame carried by said plunger, guides carried by said frame, a slide reciprocally mounted upon said guides, a cam journaled upon said slide, driving means adapted to rotate said cam, means actuated by said cam adapted to reciprocate the slide upon said guides and a work supporting member actuated by said driving means adapted to rotate the work in engagement with said grinding wheel.
30. 13. In a grinding machine, a base, a grinding wheel rotatably mounted upon the base, a plunger adjustable vertically upon the base, a reciprocally mounted slide carried by said plunger, a shaft journaled upon said slide, a worm upon said shaft, a gear adapted to be driven by the worm, a cam actuated by said gear and adapted to reciprocate the slide, a second gear adapted to be driven by said worm, a shaft driven by the last mentioned gear and means adapted to clamp a work piece upon the last mentioned shaft in position to be engaged by said grinding wheel.
35. 14. In a grinding machine, a base, a grinding wheel rotatably mounted upon the base, a slide reciprocally mounted upon the base, a shaft rotatably mounted upon the slide, a worm carried by said shaft, a gear journaled upon the slide and adapted to mesh with said worm, a cam driven by said gear adapted to reciprocate the slide and a pivotally mounted shaft operatively connected with said worm and adapted to rotate a work piece in engagement with said grinding wheel.
40. 15. In a grinding machine, a base, a grinding wheel rotatably mounted upon the base, a slide reciprocally mounted upon the base, a bearing upon the slide, a shaft journaled upon the slide, a worm upon the shaft, a gear meshing with said worm, a rotatable member upon said bearing, a cam having a portion projecting through said gear and connected with said rotatable member, means upon said base engaging the cam to cause the latter to effect reciprocation of the said slide and a work holder driven by said shaft adapted to rotate a work piece in engagement with the said grinding wheel.
45. 16. In a grinding machine, a base, a grinding wheel rotatably mounted upon the base, a slide reciprocally mounted upon the base, a shaft journaled upon the slide, a worm carried by said shaft, a bearing formed upon the slide, a gear journaled upon the bearing and meshing with said worm, a member rotatably mounted upon said bearing, a cam having a portion projecting through said gear and connected with said rotatable member, means actuated by the cam adapted to effect reciprocation of said slide, a gear driven by said worm, a member driven by said last mentioned gear, and means for clamping a work piece upon said member in position to be engaged by said grinding wheel.
50. 17. In a grinding machine, a base, a grinding wheel rotatably mounted upon said base, a slide reciprocally mounted upon the base, a shaft journaled upon said slide, a bearing upon the slide, a gear journaled upon said bearing, means actuated by the shaft for driving said gear, a cam connected with the gear and adapted to reciprocate the slide, a pivotally mounted member upon the slide

and a rotatable work holding support carried by said member and adapted to be actuated by said shaft to rotate the work in engagement with said grinding wheel.

5 18. In a grinding machine, a base having guides, a work carrying slide mounted on said guides, a shaft journaled in said slide and extending at right angles to said guides, a cam carried by said slide and connected 10 to be driven from said shaft, and means on said base adapted to engage said cam to move said slide when said shaft is rotated.

19. In a grinding machine, a base having guides, a slide carrying a work-holder 15 mounted on said guides, a shaft journaled in said slide and extending transversely of said guides, a cam carried by said slide and

ganged to said shaft, a roller carried by said base to engage said cam, and means for rotating said work-holder.

20 20. In a grinding machine, a base having guides, a slide mounted on said guides, a work-holder rotatably mounted on said slide, a driving gear therefor, a cam rotatively mounted on said slide, a driving gear 25 for said cam, a pair of rollers carried by said base on opposite sides of said cam, and a single gear on said shaft engaging both said gears, whereby rotation of said shaft simultaneously rotates and reciprocates said 20 work-holder.

In testimony whereof, I affix my signature.

HANS LUTZ.
